ABSTRACT

Apparatus for suspending elevator guide rails from the top of a hoistway and a method for employing the apparatus to lower guide rails, comprising a string of interconnected discrete guide rail sections, down a hoistway, section by section.

2 Claims, 4 Drawing Figures

FIG. 4

FIG. 3

APPARATUS AND METHOD FOR SUSPENDING ELEVATOR GUIDE RAILS

This invention relates to elevators. In particular, it concerns both an arrangement for suspending elevator guide rails from the top of a hoistway and a method of employing that arrangement for lowering the guide rails into the hoistway.

In certain types of elevator installations the hoistway, during construction, is accessible from the top only, as is the case with mine elevators. In such installations it is common practice to lower elevator guide rail sections down the hoistway over the heads of construction workers who are waiting to install those sections on the walls of the hoistway to form the elevator guide rails.

It is an object of this invention to make the working conditions of installers of mine elevators safer.

One of the features of the invention is that it enables the elevator guide rails sections to be lowered down the hoistway shaft without the necessity of construction workers being located below in the shaft while this lowering operation takes place.

Another feature of the invention is that the entire length of elevator guide rails can be suspended from the top of a hoistway in such a way that they may be secured to the side walls of the hoistway while remaining suspended from the top thereof.

According to the invention there is provided apparatus for suspending a T-shaped elevator guide rail in a hoistway shaft. This apparatus includes a pair of mounting members spanning the top of the hoistway in a direction substantially perpendicular to one side thereof. These mounting members are laterally separated sufficiently to enable the guide rail to be suspended between them with the cross-piece of the T of the guide rail being disposed substantially perpendicularly to the longitudinal axis of the mounting members. Also included in the apparatus is a guide unit which is secured to and mounted on the mounting members. This guide unit has a slot disposed outwardly toward the previously mentioned side of the hoistway for receiving the leg portion of the T of the suspended guide rail. Support means serving as a stop for the guide unit are also provided. This support means rests atop and spans the support members. It is resiliently secured to the guide unit on the outer side thereof for pressing against the back surface of the cross-piece of the suspended guide rail. With this apparatus a fish plate fixedly attached to the uppermost portion of the guide rail can be supported by the stop to suspend the guide rail in the hoistway. In addition, by locating the mounting members and the guide unit suitably with respect to the aforementioned side of the hoistway it will suspend the guide rail properly in relation to that side to enable it to be secured thereto while remaining suspended from the top of the hoistway.

Other objects, features and advantages of the invention will become apparent to those skilled in the art from the following description when considered in conjunction with the appended claims and accompanying drawing, in which

FIG. 1 is a three dimensional pictorial representation of an elevator guide rail suspended in a guide unit according to the invention;

FIG. 2 is a three dimensional pictorial representation of the elevator guide rail of FIG. 1 suspended in its guide unit taken from a different angle than FIG. 1;

FIG. 3 is a three dimensional pictorial representation of a pair of elevator guide rails suspended in their hoistway; and

FIG. 4 is a representation of the guide unit of FIG. 1.

Referring to the drawing, in FIGS. 1, 2 and 3 thereof, there is shown a pair of mounting members 11 and 12 each of which is a suitably sized channel iron. These are supported in a satisfactory manner at the top of hoistway 13 (FIG. 3) to span the hoistway so as to be disposed substantially perpendicular to its sides. These mounting members are appropriately separated laterally from each other to enable T-shaped guide rails 15 and 16 to be suspended between them with the cross-piece of each guide rail disposed substantially perpendicularly to the longitudinal axis of the mounting members.

Guide units 17 and 18 are provided for the guide rails 15 and 16 respectively. Each is mounted on mounting members 11 and 12 and secured thereto in any suitable manner, such as through the use of rail clips (not shown). Each of these guide units is provided with a slot 20 (FIG. 4) appropriately sized to receive the leg portion of the T of its associated guide rail. For this purpose each of the guide units is mounted so that its slot 20 is disposed toward the side of the hoistway to which its associated guide rail is to be secured.

Resiliently secured to respective ones of guide units 17 and 18 are support means 21 and 22. For this purpose a bolt 24 is passed through each side of each guide unit and support means. Fitted over each bolt is a coil spring 25 which is brought into compression by nut 26 being suitably threaded onto the associated bolt 24. In this way each of the support means is urged against the back surface of the cross-piece of its suspended guide rail. A rod 28 is suitably pivoted to mounting members 11 and 12 at each end thereof. A separate air cord 30 is affixed to each rod 28 and to the associated support means 21 and 22 so that each support means may be moved away from its associated guide unit against the resilient force urging it in the opposite direction by moving its associated rod 28 away from the respective guide unit.

The foregoing equipment, as will be explained, is employed to lower guide rails 15 and 16, each comprising a string of interconnected discrete T-shaped guide rail sections, down hoistway shaft 13, section by section. Upon completing this lowering operation and while remaining suspended guide rails 15 and 16 may be secured to the respective sides of hoistway 13 provided mounting members 11 and 12 and guide units 17 and 18 have been located properly with respect to the sides of the hoistway.

The steps to be taken to accomplish the foregoing lowering operation include attaching a T-shaped fish plate 32 (FIG. 1) to the back of the cross-piece of a T-shaped guide rail section with the fish plate extending beyond one end of the section. A rail hoisting plate 33 which suitably is a short section of T-shaped rail is connected to the extended end of fish plate 32. Hoist plate 33 is appropriately drilled to enable shackle 35 to be attached thereto. An appropriate hoist means 36 (FIG. 3) is then connected to this shackle to raise and suspend this first rail section with the fish plate end above the other. The rail section is then lowered with the back of its cross-piece disposed towards its associated side of the hoistway and with the leg of its T in slot 20 of the associated guide unit 17 or 18.

When fish plate 32 comes to rest on support member 21 or 22 rail hoist plate 33 is removed from fish plate 32 and connected to another such fish plate which is thereupon connected to a second rail section in a manner similar to the manner fish plate 32 was connected to the first rail section. This second rail section is raised and suspended by the agency of shackle 35 and the hoisting means 36 until its lower end can be connected to fish plate 32 to form a fish joint between the first and second rail sections. Thereupon the interconnected first and second rail sections are raised sufficiently to remove fish plate 32 from contact with the appropriate support means 21 or 22.

By moving rod 28 away from the guide rail sufficiently, support means 21 or 22 is moved away from its associated guide unit 17 or 18 sufficiently to enable fish plate 32 to be lowered past the respective support means. After this is done the respective support means 21 or 22 is returned to press against the back piece of the second rail section by releasing rod 28. The first 20 and second rail sections are then lowered by the hoisting means until the fish plate at the end of the second rail section comes to rest on the appropriate support means 21 or 22.

These operations are continued at each side of the 25 hoistway until a desired length of guide rail is suspended on each side. It should be understood that if support members 11 and 12 and guide units 17 and 18 have been disposed properly with respect to the sides of hoistway 13, and establish the desired distance between guide rails, installers can secure the guide rails to the respective walls of the hoistway from a temporary moving platform starting at the bottom of the hoistway while the rails remain suspended from their uppermost fish plates and support members 21 and 22. 35

Variations in the foregoing arrangement and the method of employing it will be obvious to those skilled in the art to which the invention relates. Accordingly it is intended that the foregoing description be considered illustrative and not limiting in any sense. 40

What is claimed is:

1. Apparatus for suspending a T-shaped elevator guide rail in a hoistway shaft to enable it to be secured to one side thereof including:
a pair of mounting members spanning the top of said 45 hoistway, in a direction substantially perpendicular to said one side, said members being separated laterally sufficiently to enable said guide rail to be suspended between them with the cross-piece of the T of said guide rail being disposed substantially 50 perpendicularly to the longitudinal axis of said mounting members;
a guide unit for said guide rail secured to and mounted on said mounting members and having a slot disposed outwardly toward said one side of said hoistway for receiving the leg portion of the T of 55 said suspended guide rail; and
support means serving as a stop for said guide unit, said support means resting atop and spanning said mounting members and being resiliently secured to 60 said guide unit on the outer side thereof for pressing against the back surface of the cross-piece of said suspended guide rail;
whereby a fish plate fixedly attached to the uppermost portion of said guide rail can be supported by 65

said stop to suspend said guide rail in said hoistway; said mounting members and said guide unit being suitably located with respect to said one side of said hoistway to suspend said guide rail properly in relation to said one side to enable it to be secured thereto while remaining suspended from the top of said hoistway.

2. A method of lowering a pair of elevator guide rails, each comprising a string of interconnected discrete T-shaped guide rail sections, down a hoistway shaft to enable them to be secured to opposite sides thereof including the steps of

- a. fixedly attaching a fish plate to the back of the cross-piece of a first one of said T-shaped guide rail sections with the fish plate extending beyond one end thereof;
- b. connecting hoisting means to said first rail section and raising and suspending said first rail section by said hoisting means with the longitudinal axis of said section disposed vertically and said one end above the other;
- c. lowering said first rail section by said hoisting means into said hoistway longitudinally with said one end above the other and the back of its cross-piece disposed toward one side of said hoistway until said fish plate rests upon a first support means located at the top of said hoistway whereby said rail section suspends from said first support means;
- d. disconnecting said hoisting means from said first rail section;
- e. repeating step "a" with a second guide rail section;
- f. repeating step "b" with said second guide rail section;
- g. while maintaining said second guide rail section suspended by said hoisting means fixedly attaching the back of the cross-piece of the other end of said second rail section to the extended end of the fish plate of said first section;
- h. raising said attached first and second rail sections sufficiently to remove the fish plate of said first section from contact with said first support means;
- i. withdrawing said first support means sufficiently from its position under the fish plate of said first section to permit said fish plate to pass by it upon said interconnected rail sections being lowered into said hoistway;
- j. lowering said interconnected rail sections until the fish plate of first section is below said first support means;
- k. returning said first support means to its original position;
- l. lowering said interconnected rail sections by said hoisting means until the fish plate of said second section rests upon said first support means;
- m. repeating step "d" for said second rail section;
- n. continuing to repeat steps "e" through "m" for additional rail sections until a desired length of the first of said pair of guide rails is suspended in the hoistway from said first support means;
- o. repeating steps "a" through "n" for the second of said pair of guide rails by the reuse of said hoisting means and the use of a second support means in place of said first support means.
